COMBINED HOUSE NUMBER SIGN AND LIGHT THEREFOR

Orville Wright, Louisville, Ky.

Application May 23, 1957, Serial No. 46,322

Term of patent 14 years

(Cl. D1—7)

I claim:

The ornamental design for a combined house number sign and light therefor, as shown.
